[57] CLAIM

The ornamental design for a furniture leg, as shown and described.

DESCRIPTION

FIG. 1 is a front perspective view of our furniture leg design; FIG. 2 is a right side view thereof, the left side being a mirror image; FIG. 3 is a front view thereof; FIG. 4 is a rear view thereof; and FIG. 5 is a top view thereof. FIG. 6 is a front perspective view of a second embodiment of our furniture leg design; FIG. 7 is a right side view thereof, the left side being a mirror image; FIG. 8 is a front view thereof; FIG. 9 is a rear view thereof; and, FIG. 10 is a top view thereof. The phantom lines in FIGS. 1 and 6 show environment structure and do not form a part of the design sought to be patented.
